UNITED STATES PATENT OFFICE.

WILLIAM H. PRATT, OF LYNN, MASSACHUSETTS, ASSIGNOR TO GENERAL ELECTRIC COMPANY, A CORPORATION OF NEW YORK.

PREPAYMENT-METER.

No. 900,777.

Specification of Letters Patent.

Patented Oct. 13, 1908.

Application filed April 10, 1905. Serial No. 254,660.

To all whom it may concern:

Be it known that I, WILLIAM H. PRATT, a citizen of the United States, residing at Lynn, county of Essex, State of Massachusetts, have invented certain new and useful Improvements in Prepayment-Meters, of which the following is a specification.

My present invention relates to a prepayment mechanism or device primarily adapted 19 for use in connection with an electric meter.

In carrying out my invention I employ a switch for controlling an electric circuit through which flows electricity purchased by the deposit of coins in the prepayment mechanism. The switch is moved into the circuit-closing position by the insertion of one or more coins into the prepayment device, and is thereafter maintained in the closed position until the instant at which the value of 20 the electricity consumed reaches that of the deposited coin or coins.

The coin or coins which are inserted in the mechanism pass into a movable chute or receptacle. The weight of the coin or coins in 25 the chute moves the latter into a different position from that occupied by it when empty. The position of the chute controls the operation of the switch, though the power for operating the switch is furnished by a 30 spring which is wound up by means which may be independent of the meter and independent of the insertion of the coin or coins.

The meter which measures the flow of electricity in the consumption circuit removes 35 the coins from the receptacle or chute from time to time as the electric value of the coin is consumed. The chute or receptacle is arranged to hold a number of coins at one time, and other coins may be placed in the chute or 40 receptacle from time to time as coins previously inserted are removed by the meter so that the switch may be maintained in the closed position indefinitely by the timely insertion of coins.

45 The various features of novelty which characterize my invention are pointed out with particularity in the claims annexed to and forming a part of this specification. For a better understanding of my invention reference may be had to the accompanying drawings and descriptive matter in which I 50 have illustrated and described one of the forms in which my invention may be embodied.

55 Of the drawings, Figure 1 is a view partly

in sectional elevation and partly in diagram illustrating the operation and arrangement of parts of the prepayment mechanism; Fig. 2 is a sectional elevation showing my prepayment device attached to an electric meter, 60 only a portion of the meter proper being shown.

Referring to the drawings, 1 represents the main frame member of an electric motor meter of the well known Thomson recording 65 watt meter type which may be inclosed in a suitable casing 2. The armature shaft 3 of the meter has its upper end journaled in a suitable bearing 3' carried by the frame. The armature 4 carried by the shaft 3 co- 70 operates with the main field coils 5 and starting coil 5' in the usual manner. On the upper side of the frame member 1 is secured a U-shaped yoke or frame 6 the legs of which extend vertically upward. Between the upper ends of the frame member 6 the combined terminal and switch contact 7 is secured by brackets 7' suitably insulated. A similar contact switch 8 is secured and insulated from one of the legs of the frame 6 by a 75 bracket 9 some distance below the contact 7. A pivoted switch member 10, the body of which may be formed of laminated copper, is carried by a shaft 11 having its ends journaled in the legs of the frame 6. The switch 80 blade 10 has secured to it spring arms 12 carrying carbon contact devices 13.

An arm 14 has one end secured to the switch member 10 for which it serves as an operating device. The outer end of the arm 90 14 carries a roller 15 which engages the edge of a cam wheel 16. The cam wheel 16 and gear wheel 17 to which it is rigidly connected are loosely mounted on a shaft 18 journaled in the legs of the frame member 6. The edge 95 of the cam wheel 16 is in the form of alternate teeth and depressions or notches 20. When the wheel is in the position in which the roller 15 engages the end of a tooth 19 the switch 10 is held in the closed position as 100 shown in Fig. 1 in which its beveled end engages the contacts 7 and 8. In this position the contacts 13 engage the contacts 7 and 8 and the springs 12 are under some tension. When the wheel is given a turn equal to half 105 the arc between the centers of adjacent teeth the roller 15 drops in the adjacent notch 20 and the switch moves into the open position. The weight of the arm 14 and the roller 15 may be relied upon to move the switch into 110

open position, though any suitable spring or similar means may be employed in addition to cause the switch to move into the open position at the proper time.

It will be readily understood by those skilled in the art that a separation occurs between the body of the switch member 10 and the contacts 7 and 8 before the carbon auxiliary contacts 13 move out of engagement with the contacts. As a result any arcing between the switch and the contacts takes place between the carbon blocks and the adjacent portions of the contacts. This prevents any injury of the main contact surface between the body of the switch 10 and the contacts 7 and 8 being injured by sparking.

A spiral spring 21 has its outer end secured to a suitable stud 22 carried by the disk and its inner end secured to the shaft 18, one end 20 of which is squared so that it may be engaged by a key which extends through the corresponding leg of the frame 6 and through the inclosing casing. By turning the shaft 18 the spring 21 may be wound up. A ratchet 25 wheel 23 carried by the shaft and co-operating pawl 24 carried by the frame 6 prevents backward rotation of the shaft 18.

The gear wheel 17 gears with a small gear 25 carried by a shaft 26 journaled in the frame 6 below the shaft 18. The gear 25 is connected to a wheel 27 which is provided with a pin or tooth 28 which projects from the wheel parallel to the shaft. An escape- 30 ment pallet 29 or device is pivoted from a bracket 30 carried by the frame. The two arms 31 of the pallet 29 are provided with projections 32 at their ends which are adapted to engage with the pin 28 in the manner hereinafter set forth. An operating arm 33 35 of the pallet extends down below the pivotal point of support and is provided at its lower end with an off-set portion 34. An inclined cam surface 35 is formed in the angle between the arm 33 and the off-set 34. A spring 35' normally tends to move the pallet from the position shown in full lines in Fig. 1 to the position shown in dotted lines in which the upper side of the right hand projection is engaged by the pin 28.

50 The outer end of a divided coin chute 36 is supported in any suitable manner as by securing it to the meter casing 2, the meter casing being formed with a slot which communicates with the coin chute. The coin chute comprises two parts hinged together at 55 38. The upper portion 39 of the coin chute may be provided with any suitable coin-introducing device such as a rotatable coin-carrier operated by a shaft 40 which extends 60 through the casing. The lower portion 41 of the coin chute, which is preferably long enough to hold a number of coins, is provided with a hook or projection 42 which engages the off-set 34 and the lower portion of the 65 cam surface 35 when there are coins in the

chute as shown in Fig. 1. A helical spring 43 having one end secured to a stationary support such as a casing proper, has its other end secured to the chute portion 41, and serves as a means for holding the chute in 70 the position shown in dotted lines in Fig. 1, when no coins are in the chute. A member 44 is pivoted to the lower side of the lower end of the chute portion 41. In the position shown in Fig. 1 an arm 45 carried by the 75 member 44 projects into the chute section 41 through a slot formed in its lower edge for the purpose and prevents the downward movement of the lowermost coin in the chute. When the member 44 is oscillated in the direction shown by the arrow the arm 45 moves out of the slot and allows the escape of the lowermost coin from the chute section. At the same time another arm 46 carried by the member 44 enters the chute section and prevents the downward movement for the time being of any other coins which may be in the chute. A counter weight 47 normally holds the member 44 in position shown in Fig. 1. An extension 48 of the member 44 serves as a 90 means by which the member 44 may be oscillated to allow the escape of the lower coin from the chute when the condition of service demands it.

Near the lower end of the frame member 95 6 is located a gear wheel 49 mounted on a shaft 50 supported by a bracket 50' carried by one of the legs of the frame 6. The gear wheel 49 meshes with and is driven by a gear wheel 52 mounted on a shaft 53 driven by 100 the counting train 51 of the meter, the counting train 51 being driven in the usual manner by the meter. From one side of the wheel 49 projects a pin or stud 54. A weight 55 is loosely mounted on the end of the shaft 50. 105 The rotation of the gear wheel 49 in the direction indicated by the arrow causes the pin to engage the weight 55 in the position in which the weight hangs below the shaft 50 and carry it to the position in which it is directly over 110 the shaft. The weight 55 then immediately moves under the influence of gravity to the position in which the weight is below the center of gravity where it will remain stationary until the pin has made a half revolution after 115 which the weight will again move with the wheel 52 during a half turn of the latter. The weight 55 carries a projection 56 which engages the free end of the projection 48 as the weight falls from its top position to its 120 lower position. The momentum of the weight 55 when it strikes the arm 48 is sufficient to oscillate the member 44 and discharge the lower coin from the chute. If there is only one coin in the chute when the 125 weight engages the arm 48 the chute section will when freed from the weight of the coin move upward under the action of the spring 43. If there are one or more coins in the chute, however, as soon as the lowermost 130

coin moves out of the chute the arm 44 under the action of its counter weight moves back into the position shown in full lines in Fig. 1, and the second coin is dropped into the lowermost position. This will take place without any movement of the chute section 41.

In Fig. 1, 60 represents one of the current supply conductors. The other supply conductor 61 is connected to the contact member 7. A conductor 62 leads from the contact member 8 to one terminal of the field coils 5 of the meter. The other terminals of the field coils 5 which are in series is connected to the conductor 63 which with the conductor 60 forms the supply mains for the consumption circuit, and may supply current to any of the ordinary translating devices such as incandescent lamps 64. The armature circuit of the meter which may include a resistance 65 and starting coil 5', is connected to the lines 60 and 62 at points 67 and 68, respectively.

In the condition of the apparatus shown in Fig. 1 the switch is held in the closed position by reason of the engagement of the roller 15 with the outer edge of one of the teeth 19 of the wheel 16. The meter has just moved the wheel 52 into the position in which the pin 54 has carried the weight 55 over its center of gravity. The weight is shown in the position in which it engages the operating arm 48 of the member 44. As before stated, the momentum of the weight is sufficient to oscillate the member 44 and discharge the lowermost coin in the chute section 41. The coin thus discharged passes into the coin box or receptacle (not shown) through suitable conduit or chute 69. As soon as the lowermost coin is discharged the member 44 swings back to the position shown in the drawings under the action of the weight 47. When the consumption of current has been such as to cause a sufficient number of revolutions of the wheel 52 to discharge all of the coins in the hinged coin chute section the latter will move upward under the action of the spring 43. As the projection moves up the lower arm of the pallet will swing to the left under the action of the tension spring. This will cause the pallet to move out of the position in which it controls the pin 28 whereupon the wheel 27 will be set in motion by the spring which has been previously put under tension by winding up, by rotating the shaft 18. The movement of the wheel will be arrested by the engagement of the pin with the upper side of the right hand arm of the pallet. The gear wheels 17 and 25 are so proportioned that a half turn of the gear wheel 25 corresponds to a movement of the cam wheel 16 from the position in which the roller engages a tooth 19 of the wheel 16 as shown in Fig. 1 to a position in which it drops into the adjacent depression 20. As the roller drops into the depressions

the switch 10 opens thus interrupting the flow of current through the consumption circuit. Upon the subsequent insertion of a coin in the chute its weight causes the chute to move into the position shown in Fig. 1. The downward movement of the projection along the cam surface 35 throws the operating arm 33 of the pallet to the right against the action of its controlling spring and causes the right hand arm of the pallet to release the pin 28, whereupon the wheel 27 will make another half turn before it is checked by the engagement of the pin 28 with the left hand arm of the pallet. The movement of the wheel 27 corresponds to a movement of the cam wheel 16 sufficient to bring the roller 15 again in contact with the periphery proper of the disk thus again closing the switch allowing current to flow through the consumption circuit.

The operation of the mechanism described is positive and reliable. The power for operating the switch is furnished by the spiral spring 21 which is manually put under tension. The power necessary to carry the weight 55 used to trip the member 44 and discharge coins from the chute from its lower position to its upper position is not great, as the weight is comparatively small and the rate of elevation of the weight comparatively slow. As a result the extra work necessary to be performed by the meter on account of the prepayment attachment is such that a meter having the ordinary torque characteristic can be used without change in design.

The mechanism is one which appeals to the consumer as it is practically automatic, the only thing for the consumer to do being to rotate the coin-carrier on inserting the coin, and as the method of operating the coin-carrier does not affect in any manner the operation of the device the instrument is protected from injury by reason of improper operation in inserting coins. The spiral spring 21 may be wound up by the collector who removes the coins deposited in the meter. The spring is so arranged that the shaft can be given a number of turns before the spring is wound up, and as one revolution of the cam wheel 16 corresponds to the cancellation of value by the meter of a number of coins (in the mechanism shown), it will be readily understood that enough coins to exhaust the tension of the spring will not be inserted in the period between the visits of the coin-collector.

Should there be a failure to wind the spring up at the proper time the consumer would not derive any undue advantage therefrom as the wheel 16 would stop in the switch opening position. This is because the tension of the spring necessary to move the roller 15 out of a depression in the wheel and thereby close the switch is much greater than the tension of the spring necessary to move the wheel from the position in which the

switch is closed to the position in which it is open.

It will be obvious to those skilled in the art that changes may be made in the form in which I have embodied my invention without departing from the spirit thereof, and I do not wish the claims hereinafter made to be limited to the specific construction shown, more than is made necessary by the state of the art.

What I claim as new and desire to secure by Letters Patent of the United States, is,—

1. In a prepayment device, a meter, a switch, operating means therefor including a movable coin chute arranged to be held in one position when empty and in another position when one or more coins are contained therein, mechanism normally preventing the escape of coins from the chute, and means controlled by the meter for releasing coins from the chute one at a time.
2. In a prepayment mechanism, a switch, a pivoted coin chute arranged to be held in one position when empty and in another position when one or more coins are contained therein, and switch-operating means controlled by the position of said chute whereby when the chute is empty the switch is open and when it contains one or more coins the switch is closed.
3. In a prepayment device, a meter, a switch, a movable coin chute arranged to be held in one position when empty and in another position when one or more coins are contained therein, means controlled by said meter for controlling the release of coins from said chute, and operating means for said switch controlled by the movement of said chute.

4. In a prepayment device, a meter, a switch, operating means therefor including a movable coin chute arranged to be held in one position when empty and in another position when one or more coins are contained therein, a catch normally preventing the escape of coins from said chute and adapted by its movement to release one coin at a time, a weight pivoted at a point remote from its center of gravity, and means driven by the meter for moving the weight over its center of gravity, said weight being arranged to strike said catch in its descent.

5. In a prepayment device, a coin chute, a catch normally retained by the action of gravity in a position to prevent the escape of coins therefrom and adapted when moved to release one coin at a time and to return automatically to its normal position, a weight pivoted at a point remote from its center of gravity, and means for moving the weight over its center of gravity, said weight being arranged to strike and move said catch in its descent.

6. In a prepayment device, a meter, a switch, a movable coin chute adapted to be shifted by the insertion of a coin, a switch controlling member operatively connected to said chute, and means controlled by the meter for controlling the escape of coins from the chute.

In witness whereof, I have hereunto set my hand this seventh day of April 1905.

WILLIAM H. PRATT.
